VACUUM CIRCUIT INTERRUPTERS

James M. Lafferty, Schenectady, N.Y., assignor to General Electric Company, a corporation of New York
Filed July 24, 1958. Ser. No. 758,615
18 Claims. (Cl. 200—144)

The present invention relates generally to vacuum-type electric circuit interrupters uniquely adapted for use in inductive circuits wherein the current interrupted is of low magnitude.

The phenomena of electric current interruption in atmospheric or higher pressures, on one hand, and in high vacuum, on the other hand, are extremely complex and basically different in nature. So also, are the problems which must be overcome in producing operative devices to perform either function. Thus, for example, one great problem in non-vacuum circuit interrupters is the deterioration of the contacts thereof due to the formation of oxides of the contact metal and other chemical compounds due to the presence of atmospheric air, a protective gaseous atmosphere, or an oil bath. Any compound so formed is readily separated from the interrupter contacts. Such a continuous formation and removal of non-metallic compounds rapidly causes the interrupter contacts to erode and deteriorate.

In the vacuum interrupter, on the other hand, the complete absence of gases or liquids in contact with the interrupter contacts virtually precludes the formation of contact-eroding oxides and compounds.

Other problems, however, not generally considered or significant in the non-vacuum circuit interrupter, are of prime importance in the construction of vacuum circuit interrupters. Vacuum interrupters designed to interrupt alternating currents operates substantially as follows:

When an arc is struck between the electrodes of a vacuum interrupter, as for example, by the opening of a pair of switch contacts maintained in a vacuum of 10^{-4} mm. of mercury pressure or less, the arc vaporizes some of the electrode material. If the contacts have been properly processed to remove therefrom all occluded and sorbed gases, only ionized metallic vapor is present in the arc. The arc continues until the alternating current sought to be interrupted falls to a natural zero value, as normally occurs once each alternation. When this occurs, the arc is extinguished, and the ionized metallic particles rapidly diffuse to the cold vacuum chamber walls where they are cooled and de-ionized. When the interrupted current seeks to rise again, the arc cannot be reestablished because of the high dielectric strength of the vacuum separating the interrupter contacts. Thus, in a vacuum circuit interrupter, the current is usually completely extinguished at the first naturally occurring instantaneous zero value of current.

The foregoing occurs satisfactorily in vacuum circuit interrupters operating to interrupt alternating currents of high current ratings, namely of 500 amperes or greater. For lower values of alternating current, the phenomenon generally denominated as "chopping" occurs. At these low alternating current values, the arc, rather than persisting until the first natural current zero, is abruptly extinguished at some low current value and falls instantaneously from that value to zero. The value of current at which instantaneous arc extinction occurs is denominated the "chopping current" of the device. Typical chopping currents in prior art vacuum interrupters may be from 10 to 40 amperes. While chopping in vacuum interrupters associated with capacitive circuits may be tolerated, it is unacceptable with inductive loads because of voltage surges induced therein by the high rate of change of cur-

2

rent with time (di/dt) when an interrupter "chops." This may be seen from the relationship:

$$V = I_0 \sqrt{\frac{L}{C}}$$

V =the surge voltage induced by chopping

I_0 =the chopping current

L =the equivalent inductance of the circuit

C =the equivalent capacitance of the circuit,

and the fact that surge impedances for many inductive devices may be as high as many tens of thousands ohms.

For most industrial inductive circuit loads, it is necessary to reduce the chopping current level of a vacuum circuit interrupter to a value of below 4 amperes and, in most instances to a value of below 2 amperes.

Accordingly, it is an object of the present invention to provide vacuum circuit interrupters suitable for interrupting low value alternating currents in inductive circuits.

A further object of the invention is to provide a vacuum circuit interrupter capable of reducing the value of instantaneous alternating current changes upon interruption thereof to a value of several amperes.

Still another object of the invention is to provide vacuum circuit interrupters having arc electrodes which minimize chopping and have hardness and brittleness characteristics which avoid permanent welding-together of the contacts or shattering thereof.

In accord with the present invention, a vacuum circuit interrupter is provided in the form of an evacuable chamber capable of maintaining a vacuum of less than 10^{-4} mm. of mercury, which chamber contains a pair of opposed arc-electrodes adapted to be the terminal points of an electric arc carrying the current to be interrupted.

The portions of the arc electrodes which serve as such terminal points are substantially free of occluded and sorbed gases and are formed primarily of an intermetallic compound having a melting point in excess of 800° C. and comprising elements which are stable in air and may be conveniently vacuum-treated to remove gaseous impurities. At least one of the elements comprising the compounds utilized is selected to have a vapor pressure less than that of cadmium and greater than that of lanthanum. In a preferred embodiment of the invention, the chosen compound also comprises a metal having a low work function.

The novel features believed characteristic in the present invention is set forth in the appended claims. The invention itself, however, together with further objects and advantages thereof, may best be understood by reference to the following description taken in connection with the attached drawing in which:

FIG. 1 is a representative view of a vacuum-type circuit interrupter constructed in accord with the present invention and,

FIG. 2 is a graphical representation of a sinusoidal alternating current illustrating the effect of the chopping phenomenon.

In FIG. 1 an interrupter chamber 10 comprises a wall member 11 which may be cylindrical in shape and is constructed of a suitable insulating material, having at the ends thereof a pair of metallic end members 12 and 13 closing the volume therein to form an interrupter chamber. Suitable seals 14 are provided between casing 11 and end members 12 and 13 to render the interrupter chamber vacuum-tight.

Located within chamber 10 are a pair of separable contacts or arc-electrodes 15 and 16 shown in their closed circuit or engaged position. Upper contact 15 is a stationary contact suitably attached electrically and mechanically to a conducting rod 17 which, at its upper end, is

united electrically and mechanically with end member 12. Lower contact 16, mounted upon and electrically united with a suitable conducting rod 18, is movable and is connected through bellows 20 or an equivalent vacuum tight member permitting reciprocating motion. Terminal mount 18 projects through a suitable orifice in end member 13, and suitable actuating means may be connected thereto to impart reciprocating motion to rod 18 to cause contact 16 to enter into engagement with, and be removed out of engagement with contact 15. For certain types of interrupters, as for example, vacuum fuses and lightning arresters, electrode 16 need not be movable but may be spaced apart from electrode 15 a suitable distance. The electrical circuit which is sought to be interrupted by the interrupter device may be completed by making suitable connections to contact 21, electrically and mechanically mounted upon end member 12 and terminal 22, electrically and mechanically mounted upon rod 18. A suitable insulator shield, such as metallic cylindrical member 23, capped with an arc-preventing ferrule 24 is interposed between electrodes 15-16 and insulator 11 to prevent the latter from becoming coated with metal.

The volume within interrupter chamber 10 is suitably evacuated through an exhaust tubulation (not shown) during the final assembly thereof. For proper operation of the interrupter as a vacuum-type interrupter of alternating currents, the pressure within chamber 10 must be maintained at a pressure at least as low 10^{-4} mm. of mercury, but is preferably maintained within the range of 10^{-5} to 10^{-8} mm. of mercury. The foregoing requirement is essential for the operation of the devices as vacuum interrupters of alternating currents. This requirement is necessary because, in order that the current-carrying arc struck between electrodes 15 and 16 be extinguished at the first occurring current zero value, there must be substantially no ionizable gas present within chamber 10. The occurrence of ionization may be substantially prevented if the possible breakdown paths between electrodes 15 and 16, or their respective supports, are small with respect to the mean free path of an electron within the atmosphere obtained within the device. This mean free path is designated as the statistical distance which an electron may travel without colliding with a gas molecule at a given pressure. These conditions may be established in operative circuit interrupters only when the pressure within interrupter 10 chamber is below 10^{-4} mm. of mercury and preferably below 10^{-5} mm. of mercury.

In FIG. 2 of the drawing there is shown, in graphical form, an illustration of the chopping phenomena. In FIG. 2, the instantaneous value of a sinusoidal alternating current which is sought to be interrupted by a vacuum circuit interrupter is plotted for one-half cycle. As the current depicted by curve A rises from instantaneous value of zero, the contacts, as for example contacts 15 and 16 in FIG. 1, are separated, at point B causing an arc discharge to be established therebetween. This arc discharge is sustained exclusively by the metal evaporated from contacts 15 and 16 by the heat generated at the contact surfaces by the arc. The terminal points of the arc are known respectively as cathode and anode spots. As a matter of practice, most of this evaporation occurs at the cathode, or negatively maintained electrode. It is, however, difficult to predetermine which electrode is negative at a particular instance when an alternating current circuit is interrupted. In FIG. 2 the value of current in the arc follows its natural course along the sinusoid of curve A and, for high current arcs (those above 500 amperes) follows the dotted line until a zero value is reached. At this instant the arc is extinguished and the energized metallic ions between the electrodes rapidly diffuse to the cold walls of members 12, 13 and 23 where they are cooled and deionized. The arc remains extinguished because, when a high voltage builds up between contact 15 and 16, the arc is not reestab-

lished, due to the high dielectric strength of the vacuum separating the contacts.

In the operation of vacuum circuit interrupters where-in the current sought to be interrupted is of a relatively low value (below 500 amperes) the instantaneous current value does not follow the dotted line continuously to a zero value but, rather, at some low current value, denominated by I_0 and occurring at a time t_0 , the arc is abruptly and prematurely extinguished. This results in an instantaneous change of current from a value of I_0 to zero. The value I_0 is referred to herein as the chopping current value for a particular device. As will be readily appreciated, this almost instantaneous change of current from I_0 to zero results in a high rate of change of current with time (di/dt) and results in the production of extremely high surge voltages and inductive loads which may be connected thereto. These surges may cause the breakdown of insulation and are generally highly injurious to electrical equipment.

In the copending application T. H. Lee and J. D. Cobine, Serial Number 750,784 filed concurrently herewith, it is disclosed that chopping of low level alternating currents in vacuum circuit interrupters may be caused by an unstable condition resulting from a preponderance of arc-constricting magnetic pressure over opposing vapor pressure in the region of the electrodes between which the arc is struck. As a remedy to the chopping problem, it is shown therein that vacuum circuit interrupters may be constructed utilizing arc-electrodes comprising particular high vapor pressure materials, so that sufficient vapor pressure is available to counterbalance the arc-constricting magnetic pressure.

Although the contact materials contemplated by the aforementioned Lee and Cobine application are quite satisfactory in providing low values of chopping current in the interruption of low current alternating currents, certain of these materials in elemental form tend to be relatively soft to have low melting points. As a result of these characteristics, the elemental metals may be readily eroded and, when melted at the arc temperature, tend to weld and stick. Additionally, certain low melting point electrodes have an undue tendency to weld under the heating effect of momentary currents before the arc-electrodes are separated and an arc is struck.

In accord with the present invention at least one of electrodes 15 and 16, and in some instances both of these electrodes, are composed of intermetallic compounds at least one constituent of which is a metal having a vapor pressure lower than that of cadmium and higher than that of lanthanum. The intermetallic compounds are further characterized as having melting points higher than 800° C. and being composed of metallic constituents which are stable in air and which may be suitably processed by vacuum melting and similar techniques to provide the metal in pure form, suitable for the formation of a pure intermetallic compound suitable for use in the devices of the present invention. The requirement that one of the constituents of the intermetallic compound have a vapor pressure between that of cadmium and lanthanum needs no elaboration. The requirement that each of the constituents of the compound be stable in air may be defined as requiring that degree of stability sufficient so that, when the metal is exposed for extended lengths of time to atmospheric air at room temperature, no reaction occurs between the metal and the atmosphere other than the formation of a thin oxide coating, the order of a few molecules thick. Such coatings are commonly formed by most known metals, even those regarded as the most stable in air. The requirement that the constituents of the intermetallic compounds utilized in the present invention be suitable for processing vacuum melting or similar processes is simply that the material be one whose vapor pressure does not cause vaporization or sublimation before melting in vacuum-melting, or similar processes, and one which is not so reactive that it cannot be contained in a suitable vessel while vacuum processing is performed.

As it is well known to the art, an intermetallic compound, although falling within the broad definitions of the term "alloy," is actually a binary chemical compound between two metallic constituents wherein the proportion of the constituents occurs in fixed integral ratios and wherein a definite crystal lattice structure of quite complicated nature which has regular characteristics is formed. The characteristics of the compound generally depend upon the nature and type of the crystal lattice. Thus, for example, certain intermetallic compounds (especially those between metals of groups 3 and 5 of the periodic table) possess a crystal lattice structure adapted to the complete filling of an energy band with electrons, so that the intermetallic compound actually displays, semiconducting, rather than metallic, characteristics. Although, in general, such intermetallic compounds are not suitable for use as arc electrodes or contacts in the devices of the present invention reference is made herein to them in order to emphasize the unique and unusual characteristics which intermetallic compounds, in general, may possess.

The intermetallic compounds which I have found to be ideally suited for arc-electrodes or contacts in the vacuum circuit breakers of the present invention include: Cu_2Ce , Cu_4La , Al_2Ce , Al_2La , $AlSb$, Bi_3Ce_4 , Bi_2Mg_3 , $SnCe_2$, $SnLa_2$, $PbLa_2$, and $MgSb$.

Arc electrodes having portions thereof suitable to be utilized as the terminal points for an alternating current arc to be interrupted in vacuum made from the intermetallic compounds of the invention, exhibit the advantages of the generic class of materials set forth in the aforementioned Lee and Cobine application. Additionally, these intermetallic compounds generally possess unusually high melting points, even as compared with either constituent from which they are formed. The desirability and the great utility in utilizing high melting point materials for vacuum switch arc-electrodes are set forth hereinbefore. A further advantageous characteristic is that the intermetallic compounds utilized herein are quite brittle, without being so brittle as to be so fragile that their use as contacts in a vacuum arc interrupter is precluded.

As an example of the unusually high melting points of the intermetallic compounds utilized in accord with the present invention, Al_2Ce , although composed of constituents having melting points of $660^\circ C.$ and $830^\circ C.$ respectively, has a melting point of approximately $1465^\circ C.$ Likewise, Al_2La , although composed of constituents having a melting point $660^\circ C.$ and $812^\circ C.$ respectively, exhibits a melting point of approximately $1424^\circ C.$ $AlSb$, although composed of constituents having melting points of $660^\circ C.$ and $630^\circ C.$ respectively, exhibits a melting point of approximately $1050^\circ C.$ Bi_3Ce_4 , although composed of constituents having melting points of $262^\circ C.$ and $830^\circ C.$ respectively, exhibits a melting point of approximately $1600^\circ C.$ Bi_2Mg_3 , although composed of constituents having melting points of $262^\circ C.$ and $650^\circ C.$ respectively, exhibits a melting point of approximately $823^\circ C.$ $SnCe_2$, although composed of constituents having melting points of $232^\circ C.$ and $830^\circ C.$ respectively, itself exhibits a melting point of $1400^\circ C.$ $SnLa_2$ although composed of constituents having melting points of $232^\circ C.$ and $812^\circ C.$ respectively exhibits a melting point approximately $1420^\circ C.$ $PbLa_2$, although composed of constituents having melting points of $327^\circ C.$ and $812^\circ C.$ respectively, exhibits a melting point of approximately $1315^\circ C.$ $MgSb$, although composed of constituents exhibiting melting points of $630^\circ C.$ and $650^\circ C.$ respectively, exhibits a melting point itself of $1228^\circ C.$ In view of the foregoing, it may readily be seen that intermetallic compounds utilized in the present invention possess unique and unexpected high-melting point characteristics which suit them ideally for use as the arc-electrodes of the vacuum circuit interrupters of the present invention. To further illustrate the characteristics of the intermetallic compounds of the present invention as contrasted with characteristics of their constituents, reference is

made to the following table (Table I) wherein the melting points and approximate vapor pressures of certain illustrative intermetallic compounds which may be utilized in the circuit interrupters of the invention are given, along with the melting points and approximate vapor pressures of their constituents. It may readily be seen that the approximate vapor pressures are very nearly the same for the compounds and the constituents thereof, but that the melting points of the compounds are generally substantially higher than the melting points of either of the constituents thereof.

Table I

	Electrode Material or Constituent	Melting Point ($^\circ C.$)	Vapor Pressure at $800^\circ K.$ (mm. Hg)
15	C_1	1,083	$\sim 2 \times 10^{-2}$
	L_2	812	$\sim 10^{-1}$
	Ce	830	$\sim 10^{-6}$
20	Al	660	$\sim 6 \times 10^{-11}$
	S	630	$\sim 6 \times 10^{-3}$
	Bi	262	$\sim 2 \times 10^{-4}$
	M_3	650	$\sim 1.5 \times 10^{-1}$
	Sn	232	$\sim 10^{-10}$
	P	327	$\sim 5 \times 10^{-4}$
25	Al_2Ce	1,405	$\sim 10^{-6}$
	Al_2La	1,424	$\sim 10^{-7}$
	$AlSb$	1,050	$\sim 6 \times 10^{-3}$
	Bi_3Ce_4	1,600	$\sim 2 \times 10^{-4}$
	Bi_2M_3	823	$\sim 1.5 \times 10^{-4}$
	$SnCe_2$	1,400	$\sim 10^{-6}$
	$SnLa_2$	1,420	$\sim 10^{-6}$
	$PbLa_2$	1,315	$\sim 5 \times 10^{-4}$
	$MgSb$	1,228	$\sim 6 \times 10^{-3}$
30	$C_{12}Ce$	820	$\sim 10^{-6}$
	Cu_4La	860	$\sim 10^{-7}$

That the melting point of vacuum alternating circuit current arc interrupters is important in preventing excessive melting in the contacts and, more important, in preventing the contacts from welding together, may readily be seen from fact that the cathode spot of a vacuum arc interrupter, such as is utilized as to interrupt currents several hundred amperes magnitude at 600 volts, often has a temperature of $2500^\circ K.$ to $3500^\circ K.$

A further unexpected advantage obtained in vacuum arc interrupter utilized for the interruption of alternating current in accordance of the present invention, by utilizing the intermetallic compounds set forth herein, is the highly desirable intermediate brittleness of these compounds as compared with other elements and alloys having other desirable characteristics. As is well known to the art, welding together of the contacts of the vacuum switch is a serious problem. If a weld between two contacts composed of a relatively ductile element, such as bismuth, does tend to form, the weld may withstand the initial shock of an attempt to separate the contacts, so that a permanent juncture therebetween is formed. The intermetallic compounds of this application, however, are all quite hard and brittle and, should an initial welding action tend to take place, this brittleness, with the attendant lack of tensile strength, allows for such an initial weld to be broken so that the contacts do not permanently join together. The brittleness of the intermetallic compounds of the present invention does not, however, approach the point, as does that of certain other elements and alloys, where shattering of the contacts becomes a problem.

As a condition precedent to satisfactory operation to 65 any vacuum switch, it is necessary that the electrodes, between which an arc is momentarily to exist, be substantially free of occluded and sorbed gases. This requires that the electrodes be previously conditioned in order to remove from them all sorbed and occluded gases. 70 For this reason, among others, commercially useful arc vacuum circuit interrupters have not heretofore been constructed utilizing any of the materials which comprise the intermetallic compounds of the present invention. This is primarily due to the fact that rendering 75 a material free of occluded and sorbed gases is most

effectively done by out-gassing and baking the material at an extremely high temperature. Thus, commercially available vacuum circuit interrupters have, in the past, utilized refractory metals as the electrodes thereof since these materials may be heated to temperatures of the order of 2000° C. without substantial evaporating or melting. Obviously, such treatment cannot be utilized upon the intermetallic compounds utilized in the circuit interrupters of the present invention. However, it has been found that, once certain metals have been freed of occluded and sorbed gases by suitable treatment, the material may be exposed to atmospheric or higher pressures of air or other gases without becoming contaminated other than by the formation of a thin protective oxide over the surface thereof generally of the order of molecules in thickness. Accordingly, the electrodes of the present invention may be formed by first removing occluded and sorbed gases from the constituent of the intermetallic compounds individually in their metallic state as for example, by repeated arc-meltings in a vacuum. The constituents are then carefully measured to obtain stoichiometric proportions to form the desired compound and are once again melted and mixed in vacuo and cast in the desired electrode form.

It is, of course, necessary to provide a standard for occluded and sorbed gases for vacuum interrupter contacts in order that the interrupter be operative. Such a standard may be set analytically in the requirement that the final arc electrode be of such purity as to contain less than 10^{-8} atomic parts of all gases. As a practical matter, this requirement may further be attained if contacts utilized in the present invention, when placed in a vacuumized test chamber a few liters in volume and subsequently deeply eroded by a repetitive arcing, as for example, with the voltage of commercial power at a current of 100 amperes or more, the pressure level of the container, a few cycles after arcing, does not rise substantially from its initial value in the absence of getters and pumps, even if the initial pressure is of the order of 10^{-5} mm. of mercury. Since repeated arc erosion, in accord with such a test, consumes a substantial proportion of the contact it provides a satisfactory test for the determination whether the arc-electrodes are substantially free of occluded and sorbed gases, since even the presence of an infinitesimal amount thereof would cause a substantial rise in pressure of the test chamber.

After the arc-electrodes constructed of the intermetallic compounds set forth herein have been prepared in accord with the foregoing procedures and representative samples thereof properly tested, the electrodes are assembled into the interrupter device as illustrated in FIG. 1 and the entire device is connected to a suitable vacuum pump and evacuated. While being evacuated to a pressure of at least 10^{-4} mm. of mercury or less, the entire device is suitably raised to a temperature of at least 500° C. in order "to bake out" all of the components thereof to free them from surface adsorbed gases so that an operative pressure may be maintained therein, even under high temperature conditions caused by repeated arcing between the electrodes thereof. Suitably, the device may be evacuated for approximately ten hours a pressure of 10^{-5} mm. of mercury.

After the foregoing treatments, the tubulation connecting the interrupter chamber to the evacuation means is closed off, and the device is ready for use as a vacuum circuit interrupter for alternating currents of low magnitude to provide low chopping values.

Although one object of the present invention is to provide improved chopping values for low voltage alternating current vacuum circuit interrupters by the provision of high melting point, intermediate brittleness, intermetallic compound contacts to avoid vapor starvation at the cathode electrode, another factor which can contribute to the chopping phenomenon is the presence of instabilities at the electrodes. It has been proposed to remove these in-

stabilities by utilizing, as the electrodes of the vacuum circuit breaker, a material having a low-work function. Accordingly, in accord with a preferred embodiment of the present invention, while one constituent of the intermetallic compound comprising the arc electrodes of the vacuum circuit breakers of the invention comprises a metal having a vapor pressure between that of lanthanum and cadmium and satisfying certain other conditions, the other material comprising the intermetallic compound is chosen from the metals exhibiting a work-function below 3.5 e.v. as for example, cerium or lanthanum. This constituent must, of course, also be stable in air and suitable for vacuum processing. Accordingly, while all of the intermetallic compounds identified hereinbefore provide superior arc-electrodes for vacuum arc interrupters in accord with the present invention, certain of these materials namely, Al_2Ce , Al_2La , Bi_3Ce_4 , $SnCe_2$, and $PbLa_2$ provide added insurance against the premature extinguishment of an alternating current arc by virtue of the incorporation therein of a material having a low-work function namely, cerium or lanthanum. Additionally, although the compounds Cu_2Ce and Cu_4La have melting points lower than pure copper, they are suitable as arc-electrodes due to the low-work functions of cerium and lanthanum. Thus, for example, a vacuum interrupter satisfying the criteria set forth hereinbefore and having arc-electrodes of Cu_2Ce held the chopping current to a value of 1.75 A. at low current values and successfully and repeatedly interrupted currents of 6500 A. at 15000 volts.

Although it is an object of the present invention to provide harder, intermediately brittle, and high melting point, high vapor pressure, contact electrodes for vacuum circuit interrupters utilized for alternating current circuit interruption, and the intermetallic compounds of the present invention serve this object, in certain instances greater mechanical strength than may be supplied by the materials themselves, is required. Accordingly, while the contacts of circuit interrupters constructed in accord with the present invention may be composed entirely of these intermetallic compounds, these intermetallic compounds may also be used as filler substances to fill the pores of a porous refractory matrix, as for example, tungsten, molybdenum or the carbides thereof. In accord with this embodiment of the invention the porous matrix is prepared, as for example, by sintering tungsten or molybdenum powder at high temperature and pressure. The vacuum-treated intermetallic compound is then infiltrated into the porous mass at a suitable high temperature in vacuo. In such an arrangement, the mechanical strength of the porous refractory matrix adds greatly to the ruggedness and long length characteristics of the circuit interrupter.

As is mentioned hereinbefore, presently available evidence indicates that chopping, the premature extinction of an alternating current arc before a normally occurring current zero, is primarily a phenomena which occurs at the cathode electrode. Accordingly, when suitable precautions are taken so that a given electrode may be made the instantaneous cathode when an alternating current is interrupted, in order that the advantages of the present invention be obtained. It is only necessary, in the instance of an alternating current interrupter with which these precautions are taken, that the intermetallic compounds of the invention be used for the cathode electrode. Accordingly, it is within the scope of the present invention that operative vacuum circuit interrupter which exhibits low values of chopping currents without undesirable welding or sticking characteristics may be constructed wherein only one of the arc-electrodes is fabricated of the intermetallic compounds of this invention. It is, however, contemplated in a preferred embodiment of the invention that both electrodes be constructed of these compounds, since under certain circumstances, it is difficult to ascertain which electrode will be the cathode at the instant the circuit is interrupted and it may not be feasible to provide means for establishing such certainty.

While the invention has been disclosed herein with

respect to certain embodiments thereof, it is apparent that many modifications and changes will readily occur to those skilled in the art. Accordingly, by the appended claims I intend to cover all such modifications and changes as fall within true spirit and scope of the present invention.

What I claim as new and desire to secure by Letters Patent of the United States is:

1. A vacuum alternating current circuit interrupter comprising; an evacuable envelope evacuated to a pressure lower than 10^{-4} mm. of mercury; a pair of electrical terminals adapted for connection in an alternating current circuit; a pair of electrodes located within said envelope, connected in circuit between said terminals and disposed in spaced-apart relationship during circuit interrupting operation to allow for the establishment of a circuit interrupting arc therebetween, each of said electrodes having a region on which a respective electrode spot for a low current arc may be established; one of said electrode regions being formed of an intermetallic compound having a melting point in excess of 800° C., at least one constituent of which comprises a metal having a vapor pressure greater than that of lanthanum and less than that of cadmium, all constituents of said compound being stable in air and suitable for processing in vacuo to remove gaseous impurities therefrom.

2. A vacuum alternating current circuit interrupter comprising; an evacuable envelope evacuated to a pressure lower than 10^{-4} mm. of mercury; a pair of electrical terminals adapted for connection in an alternating current circuit; a pair of electrodes located within said envelope, connected in circuit between said terminals and disposed in spaced-apart relationship during circuit interrupting operation to allow for the establishment of a circuit interrupting arc therebetween, each of said electrodes having a region on which a respective electrode spot for a low current arc may be established; one of said electrode regions being formed of an intermetallic compound having a melting point in excess of 800° C., at least one constituent of which comprises a metal having a vapor pressure greater than that of lanthanum and less than that of cadmium, all constituents of said compound being stable in air and suitable for processing in vacuo to remove gaseous impurities therefrom.

3. The circuit interrupter of claim 1 wherein the electrode region comprises an intermetallic compound selected from the group consisting of Al_2Ce , Al_2La , $AlSb$, Bi_3Ce_4 , Bi_2Mg_3 , $SnCe_2$, $SnLa_2$, $PbLa_2$, $MgSb$, Sn_2Ce , Sn_4La , Cu_2Ce and Cu_4La .

4. The circuit interrupter of claim 1 wherein the electrode region is Al_2Ce .
5. The circuit interrupter of claim 1 wherein the electrode region is Al_2La .
5. The circuit interrupter of claim 1 wherein the electrode region is $AlSb$.
7. The circuit interrupter of claim 1 wherein the electrode region is Bi_3Ce_4 .
8. The circuit interrupter of claim 1 wherein the electrode region is Bi_2Mg_3 .
9. The circuit interrupter of claim 1 wherein the electrode region is $SnCe_2$.
10. The circuit interrupter of claim 1 wherein the electrode region is $SnLa_2$.
11. The circuit interrupter of claim 1 wherein the electrode region is $PbLa_2$.
12. The circuit interrupter of claim 1 wherein the electrode region is $MgSb$.
13. The circuit interrupter of claim 1 wherein the electrode region is Sn_2Ce .
14. The circuit interrupter of claim 1 wherein the electrode region is Sn_4La .
15. The circuit interrupter of claim 1 wherein the electrode region is Cu_2Ce .
- 25 16. The circuit interrupter of claim 1 wherein the electrode region is Cu_4La .
17. The circuit interrupter of claim 2 wherein the low-work function material is cerium.
18. The circuit interrupter of claim 2 wherein the low-work function material is lanthanum.
